(57) **CLAIM**

The ornamental design for a high efficiency particulate air filter seal, as shown and described.

DESCRIPTION

FIG. 1 is a top perspective view of the filter seal showing my new design;

FIG. 2 is a bottom plan view thereof;

FIG. 3 is a bottom side elevation view thereof;

FIG. 4 is a top side elevation view thereof;

FIG. 5 is a right side elevation view thereof; and,

FIG. 6 is a left side elevation view thereof.

The broken lines shown are environmental only and form no part of the claimed design.
